ATTORNEY

UNITED STATES PATENT OFFICE

CHARLES B. TULEY, OF GLENOLDEN, PENNSYLVANIA, ASSIGNOR TO WESTINGHOUSE ELECTRIC & MANUFACTURING COMPANY, A CORPORATION OF PENNSYLVANIA

CONDENSER

Application filed September 18, 1930, Serial No. 482,859. Renewed November 13, 1931.

My invention relates to surface apparatus for condensing gaseous media and particularly to surface apparatus of the down-flow type intended primarily for condensing steam and it has for an object to provide apparatus of this character which shall be so constructed and arranged as to effectively utilize the entire cooling surface of the apparatus in order that it may operate at a high heat transfer rate.

In the copending application of J. H. Smith, Serial No. 412,800, filed December 9, 1929, and assigned to the Westinghouse Electric and Manufacturing Company, there is disclosed and claimed a form of condenser wherein the tube nest is so arranged that it embodies a longitudinally-extending cavity or passageway for the circulation of gaseous media through the condenser shell in a direction from the relatively warm or cooling water exit end of the tube nest toward the relatively cold or cooling water entrant end of the tube nest. By providing for such longitudinal circulation of gaseous media in the condenser shell, the entire tube nest is rendered highly effective for condensing purposes. In addition, the air and other non-condensable gases are removed at the relatively cold or exit end of the condenser so that, not only are all of the tubes of the nest rendered highly effective for condensing purposes, but by the provision of suitable baffles, some of the tubes at the cold end of the tube nest may be rendered highly effective for cooling the air and other non-condensable gaseous media prior to the removal thereof from the condenser.

In the aforesaid application, the longitudinally-extending passageway is located in an interior portion of the tube nest, the gaseous media to be condensed traveling radially through the tube nest toward the longitudinally-extending passageway. Such a condenser is known in the art as a condenser of the radial flow, coreless type and it is especially adapted for relatively large capacities.

In the present application, I disclose a form of condenser which is predicated on the principles set forth in the aforesaid Smith application but which is especially applicable

to condensers of the down-flow or partial radial-flow type as distinguished from the radial-flow type. In accordance with the present invention, I provide a condenser wherein the tube nest is so arranged within the condenser shell as to provide a longitudinally-extending passageway adjacent to the shell and devoid of cooling tubes for the natural, longitudinal circulation of gaseous media from the warm end of the tube nest, or region of relatively low heat head, to the cold end, or region of relatively high heat head. In accordance with my invention, the air is removed from the cold end of the condenser and suitable baffle structure is provided for directing gaseous media from the passageway over a portion of the cold end of the tube nest in order that the air may be reduced to minimum temperature before its removal from the condenser.

It is, therefore, a more particular object of my invention to provide a form of condenser of the down-flow type which shall embody a passageway devoid of tubes for the free and natural circulation of gaseous media longitudinally through the shell structure to the cold portion of the tube nest or region of relatively high heat head.

It has for still another object to provide a condenser of the foregoing character, wherein the longitudinal movement of the steam and non-condensable gaseous media from the relatively warm portion of the tube nest toward the relatively cold portion thereof shall assume a path or route which digresses from the longitudinal passageway into a portion of the coldest end of the tube nest in order that the condensable components of the longitudinally moving media may be condensed and in order that the non-condensable components may be cooled prior to their removal from the condenser shell.

These and other objects are effected by my invention, as will be apparent from the following description and claims taken in connection with the accompanying drawings, forming a part of this application, in which:

Fig. 1 is a longitudinal, sectional view, taken along the line I—I of Fig. 2, and show-

ing one form of condenser embodying my invention;

Fig. 2 is a vertical cross-sectional view taken along the line II—II of Fig. 1; and

5 Fig. 3 is a fragmentary detail view in cross-section taken along the radial line III—III of Fig. 2, showing the longitudinal passageway at the side of the shell.

Referring to the drawings, I show a down-flow type of condenser having a shell 11 provided with an inlet 12 for steam to be condensed and a hot well 13 having an outlet 14 for the discharge of condensate from the condenser. A nest of tubes 15 extends longitudinally through the shell 11 and is supported at its ends by end tube sheets 16 and 19 and, intermediate of its ends, by intermediate tube sheets 17 and 18, all of the tube sheets being secured to the shell structure in 10 a manner well understood in the art. The tube sheets divide the tube nest into sections 20, 21 and 22.

15 Cooling water is admitted through an inlet water box 23 disposed at one end of the condenser shell, this end being hereinafter referred to as the cold end, and, after passing through the tube nest in a single, longitudinal direction, it is discharged through an outlet water box 23' located at the other end of the shell, this end being hereinafter referred to as the relatively warm end. An offtake 24 is located in the cold end of the shell 11 for the removal of air or other non-condensable gaseous media from the condenser.

20 As shown particularly in Fig. 2, I prefer to so form the tube nest 15 that one side thereof is spaced from the shell structure so as to from an intervening steam delivery space 25. By means of such an arrangement, the entrant area through which steam to be condensed is admitted to the tube nest is materially enlarged as it includes one side of the tube nest in addition to the top of the tube nest. As 25 a result, the steam may more readily penetrate the nest.

25 The tube nest 15, as more clearly shown in Fig. 3, is also so arranged that the side thereof of adjacent the offtake 24 is spaced from the shell structure 11 so as to provide a longitudinally-extending passageway 26 for the free and unrestricted circulation of gaseous media longitudinally through the shell structure from the warm end toward the cold end, the intermediate tube sheets 17 and 18 being cut 30 away at 27 and 28 in order to provide openings of substantial flow-area and avoid interruption of the passage 26. Provided in the passage 26 are baffles 33 and 34 projecting inwardly from the condenser shell toward or 35 into the nest to deflect steam and gaseous media into the nest as indicated by the arrows shown in Fig. 3, whereby surplus steam as well as non-condensable gases entering the passage 26 from a preceding warmer section 40 is recirculated in a succeeding cooler sec-

tion to effect further condensation of steam and cooling of non-condensable gases. The baffle 34 is arranged in the cold section 20, and the passage 26 between the baffle 34 and the off-take 24 is filled by any suitable structure 45 70 75 80 85 90 95 100 105 110 115 120 125 130 35 to constrain the passage of gaseous media and steam among the cold section tubes before the offtake is reached.

The rain plate 36 prevents condensate from raining down into the passage 26 and the adjacent portion of the tube nest through which gaseous media is recirculated in a longitudinal direction. The plate projects inwardly from the shell structure and embodies a relatively narrow portion 37 located partly in the warm end section 22 and partly in the mid-section 21 and of sufficient width to cover the passageway 26 in that section and a relatively wide portion 38 located in sections 21 and 20 and of sufficient width to cover that portion of the tube nest through which the gaseous media is recirculated, due to the baffles 33 and 34, longitudinally toward the offtake 24.

From the foregoing description, the operation of my invention will be apparent. Steam to be condensed enters the shell structure 11 through the inlet 12 and surrounds a substantial portion of the periphery of the tube nest as the entering steam not only occupies the inlet portion 12 but the transversely-disposed steam delivery space as well.

Steam passes inwardly in each of the sections 20, 21 and 22 of the tube nest in the direction of the passageway 26 and undergoes condensation. The capacity for condensation increases from the warm to the cold end of the condenser; and, on this account, any steam entering the passage 26 and not condensed in the warm and intermediate sections, as well as non-condensable media received from these sections flows without restriction through the substantial openings 27 and 28 in the intermediate tube sheets toward the cold end of the condenser or region of highest heat head. This flow is further induced by the action of the air withdrawal means (not shown) which connects with the offtake 24, baffles 33 and 34 deflect the gaseous media thus recirculated into a portion of the cold end of the tube nest, whereby further condensation takes place and the non-condensable gases and air are cooled prior to removal thereof through the offtake 24. In other words, no attempt is made to apportion steam among the sections according to their condensing capacities but any excess steam not condensed in a warmer section is caused to recirculate among tubes of a cooler section so that such succeeding cooler section cooperates with the preceding warmer section to effect condensation of surplus steam discharged from the preceding warmer section.

From the foregoing, it will be apparent that I have devised a form of down-flow condenser which has an extraordinary capacity

for heat transfer consistent with the extent of its cooling surface, which produces condensate of maximum temperature and which cools the air and other non-condensable gases to minimum temperature.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

15 What I claim is:

1. In a condenser, the combination of a shell structure having an inlet for gaseous media to be condensed and an outlet for condensate, a tube nest extending longitudinally through the shell structure, an inlet water box disposed at one end of the tube nest and defining a cold end thereof, an outlet water box disposed at the other end of the tube nest and defining a warm end thereof, said tube nest having a portion of its periphery spaced from a portion of a wall of the shell structure so as to provide an intervening passageway for the longitudinal circulation of gaseous media, an air outlet provided in the shell structure near the cold end thereof, and baffle means disposed in the passageway between the air outlet and the warm end of the condenser for deflecting gaseous media from the passageway into the tube nest.

35 2. In a condenser, the combination of a shell structure having an inlet for gaseous media to be condensed and an outlet for condensate, a tube nest extending longitudinally through the shell structure, an inlet water box disposed at one end of the tube nest and defining a cold end thereof, an outlet water box disposed at the other end of the tube nest and defining a warm end thereof, said tube nest having a portion of its periphery spaced from a portion of a side wall of the shell structure so as to provide an intervening passageway for the longitudinal circulation of gaseous media, air outlet means provided in the shell structure near the cold end thereof, and a baffle extending transversely of the passageway and spaced, longitudinally, from the air outlet in the direction of the warm end of the tube nest for deflecting gaseous media flowing through the passageway toward the air outlet into the tube nest.

55 3. In a condenser, the combination of a shell structure having an inlet for gaseous media to be condensed and an outlet for condensate, a tube nest extending longitudinally through the shell structure, an inlet water box disposed at one end of the tube nest and defining a cold end thereof, an outlet water box disposed at the other end of the tube nest and defining a warm end thereof, said tube nest having a cut-away portion forming with

a wall of the shell structure a passageway of substantial flow-area for the longitudinal circulation of gaseous media, tube sheets disposed adjacent the ends and intermediate of the ends of the shell structure for supporting the tube nest and dividing the same into sections, said intermediate tube sheet being provided with an opening of unrestricted flow-area communicating with the passageway for the circulation of gaseous media between sections, an air outlet provided in the shell structure near the cold end thereof, and baffle means disposed in the passageway between the air outlet and the warm end of the condenser for deflecting gaseous media from the passageway into the tube nest.

4. In a condenser, the combination of a shell structure having an inlet for gaseous media to be condensed and an outlet for condensate, a tube nest supported within the shell structure and extending longitudinally thereof, an air offtake provided in the shell near one end of the tube nest, said tube nest being formed to provide, in cooperation with the shell structure, a longitudinally-extending passageway for the unrestricted circulation of gaseous media along one side of the shell toward the air offtake, and means disposed at one or more places in said passageway for diverting gaseous media from the passageway into adjacent portions of the tube nest.

5. In a condenser, the combination of a shell structure having an inlet for gaseous media to be condensed and an outlet for condensate, a tube nest extending longitudinally through the shell structure, an inlet water box disposed at one end of the tube nest and defining a cold end thereof and an outlet water box disposed at the other end of the tube nest and defining a warm end thereof, said tube nest having a portion of its periphery spaced from a portion of the side wall of the shell structure so as to provide an intervening cavity for the longitudinal circulation of gaseous media, an air outlet provided in the shell structure near the cold end thereof, and means disposed in said cavity and extending from the air outlet toward the warm end of the condenser for closing a portion of the cavity lying adjacent to said air outlet means, whereby the gaseous media is diverted from the cavity and is caused to circulate through a portion of the tube nest as it approaches the air outlet.

6. In a condenser, the combination of a shell having an inlet for gaseous media to be condensed and an outlet for condensate, an inlet water box associated with one end of the shell and an outlet water box associated with the other end of the shell, a tube nest extending longitudinally through the shell and embodying a portion for the transverse flow of gaseous media and a portion for the longitudinal flow of gaseous media, said longi-

tudinal flow portion being disposed near the end of the shell adjacent the inlet water box and said tube nest and shell cooperating to form a longitudinally-extending cavity of substantial flow-area for the circulation of gaseous media to the longitudinal flow portion of the tube nest, and means communicating with the tube nest near the end of the shell adjacent the inlet water box for removing air and non-condensable gaseous media from the shell.

7. In a condenser, the combination of a shell having an inlet for gaseous media to be condensed and an outlet for condensate, a tube nest extending longitudinally through the shell, an inlet water box associated with one end of the tube nest and defining a cold end thereof, and an outlet water box associated with the other end of the tube nest and defining a relatively warm end thereof, said water boxes providing for circulation of cooling water in a single, longitudinal direction through the tube nest and said tube nest being formed to provide a longitudinally-extending passageway for the circulation of gaseous media along one side of the condenser shell, a baffle extending from the side of the shell over the passageway and into the tube nest, said baffle extending a greater distance into the tube nest at the cold end than at the warm end of the tube nest, and an air offtake in communication with said passageway near the cold end of the tube nest.

In testimony whereof, I have hereunto subscribed my name this 16th day of September, 1930.

CHARLES B. TULEY.
